HENRY W. O'DOWD, OF JERSEY CITY, NEW JERSEY, ASSIGNOR TO STANDARD GAS EQUIPMENT CORPORATION, A CORPORATION OF MARYLAND.

GAS BURNER.

Application filed September 8, 1926. Serial No. 134,151.

This invention relates to improvements in heating apparatus, and has particular reference to an improved form of Bunsen burner adapted to be readily connected to or disconnected from a gas supply pipe or the like.

In many gas burner installations, as for example, in gas broilers, water heaters, etc., it is frequently necessary to remove the burners for cleaning, adjustments or repairs.

10 The devices in use prior to this invention have been objectionable because such burners have not been capable of convenient removal and replacement. Usually they have included threaded fastening elements which 15 have required manipulation, and in many instances the burners have required tilting into different planes during insertion or removal. These and other objections are overcome by the present invention, which in 20 its broader aspects contemplates a gas burner connection of such a character that the burner may be removed from or applied to a gas nozzle by a direct lateral movement relative to said nozzle.

25 More specifically, the invention comprehends the provision of a gas burner of the Bunsen type having a gas tube and a gas nozzle so constructed and arranged as to permit relative movement in a direction transverse to the axis of the gas nozzle.

Another feature of the invention is the provision of such a device with improved and simplified means for holding the burner and nozzle against accidental displacement, such means being preferably incorporated 35 with a shutter valve.

Another feature of the invention resides in the provision of an improved shutter valve for controlling admission of primary air to 40 the burner.

Other features and advantages will be apparent from the following description, reference being had to the accompanying drawings, wherein one embodiment of the 45 invention is shown by way of illustration, and wherein,

Figure 1 is a front elevation of a gas broiler having burners constructed in accordance with the invention;

50 Figure 2 is a side elevation of the burner

shown at the right in Figure 1, parts being in section, and the dotted lines showing the burner in process of removal;

Figure 3 is a bottom plan view of the mixing tube per se. 55

Figure 4 is a similar view of a shutter valve per se, adapted for use with the mixing tube of Figure 3;

Figure 5 is a similar view showing the mixing tube and shutter valve in assembled 60 relation with the valve in locked position; and

Figure 6 is a view similar to Figure 5 but showing the shutter valve in unlocked 65 position. 65

In the drawings, the invention has been shown as applied to a gas broiler, but it is not restricted to such use since it is equally adaptable for use in other environments. Such an installation may comprise a broiling 70 oven 10 of any ordinary or preferred design, and equipped with Bunsen burners 11, here shown as two in number, one at each side of the oven. The two burners 11 are alike, and therefore a detailed description of one will 75 suffice to convey a full understanding of the invention. 75

Each burner 11 comprises a horizontal member or burner proper 12, provided with a plurality of suitable flame ports 13, preferably directed toward the interior of the broiler. The member 12 is hollow and extends through the front wall of the oven 10, being removably mounted, and having its inner end supported in such position by means of a lug 14, see Figure 2, in engagement with a suitable support not shown. A mixing tube 15 communicates with the member 12 and may preferably be formed integral therewith, extending downwardly outside of the oven and toward a gas supply pipe or manifold 16. The mixing tube 15 is preferably tapered as shown, and adjacent its extremity, the walls of said tube flare outwardly to form an enlarged mouth 17 having a transverse web 18 at its outer end. 80

Extending upwardly through a central orifice 19 in the web 18 is a gas nozzle 20 which terminates within the mouth 17 and is attached to the gas supply pipe 16, the 100

flow of gas through said nozzle being controlled by a cock 21. There is, of course, a nozzle 20 provided for each burner, each nozzle being preferably in axial alinement with its corresponding mixing tube 15. The web 18 may be formed as an integral part of the mouth 17, or may comprise a separate piece of metal secured in any suitable manner to the mouth. In order to admit primary air to the mixing tube, the web 18 is provided with a plurality of openings 22, here shown as two in number, of general sector shape, and disposed at opposite sides of the orifice 19. The mouth of the mixing tube is further provided with a shutter valve 23 for controlling the amount of air passing through the openings 22, said valve being preferably cup-shaped and rotatably mounted in close engagement with the web 18 and outer wall of the mouth 17. The web 24 of the valve 23 is similar to the web 18, being provided with a central orifice 25 through which the nozzle 20 is adapted to extend and with a pair of apertures 26 for selective registration with the openings 22.

It will be evident that, with a construction as thus far described, the burner could only be removed from operative position in the broiler by lifting the burner with its shutter valve until it has cleared the end of the nozzle 20 and then moving it laterally, and the same operations are necessary, in reverse order, to replace the burner. This limitation has constituted a serious defect in the art, which the present invention overcomes.

To this end, the web 18 is formed with a slot 27 which extends radially from the central orifice 19 in the same direction as the burner member 12, and continues into the wall of the mouth portion 17 to a point above the end of the nozzle 20. Similarly, the shutter valve 23 is formed with a slot 28 extending radially from the orifice 25 and through its side wall 29. In order to reinforce the web 24 of the valve, the marginal edges of the slot 28 and orifice 25 may be thickened as at 30, which is additionally advantageous in that it provides a greater surface for the web 50 against the side of the nozzle. It will be seen that with the mixing tube 13 and shutter valve 22 constructed as thus described, the gas burner 11 can be set in place, as shown in Figures 1 and 2, with a direct lateral movement, or a movement in a direction transverse to the axis of the nozzle, and without changing the plane of the burner.

When first assembling the parts, the valve is positioned on the end of the mixing tube with the slots 27 and 28 in registration, whereupon the horizontal member 12 is inserted in the wall of the oven 10 and pushed rearwardly until the nozzle arrests further movement by contact with the edge of the orifices 19 and 25 as shown in Figure 6.

The valve may then be rotated to a position such as shown in Figure 5 or any intermediate position dependent upon the amount of air desired in the mixing tube. It is to be noted that when the valve is thus turned, it positively prevents accidental displacement of the burner relative to the nozzle by virtue of the nozzle being engaged at opposite sides by the edges of the respective orifices 19 and 25. When it is desired to remove a burner from the broiler, the valve 23 need only be rotated until its slot 28 overlies the slot 27 in the end of the mixing tube, whereupon the burner and its associated parts may be withdrawn by a direct lateral movement, as indicated by dotted lines in Figure 2.

From the foregoing it will be obvious that a substantial improvement has been made in the gas burner art. In its broader aspects, the invention is not limited to the precise construction shown and described, nor is its use limited to the particular type of heating apparatus shown, as many changes may be made in the details of the invention and it may be applied to a wide variety of gas heaters without departing from the scope of the invention or sacrificing its chief advantages.

Having thus described my invention, what I claim is:—

1. In a Bunsen burner, a mixing tube, a gas nozzle extending into the end of said tube, one side of said tube being slotted at its extremity to provide clearance for said nozzle, and locking means attached to the mixing tube, said locking means being formed so as to selectively obstruct or uncover the slot in the mixing tube.

2. In a Bunsen burner, a mixing tube having an open mouth, the wall of the tube being slotted at one side of said mouth to permit lateral passage of a gas nozzle which extends into said mouth, and a shutter valve rotatable on the mouth and about the gas nozzle, said shutter valve having a slot adapted for registration with the slot in the tube wall, such construction preventing relative lateral movement between the nozzle and the tube when said slots are out of registration.

3. A Bunsen burner provided with a mixing tube having a web at its mouth formed with an air inlet, a shutter valve rotatably mounted upon said mouth and being formed with an aperture adapted to register with said air inlet, said tube and shutter valve being formed each with a slot adapted to be brought into or out of registration with each other; whereby the burner may be applied to or removed from a gas nozzle by a relatively lateral movement, and whereby the shutter valve may be rotated to regulate the supply of air to the tube and also to lock the tube in place.

4. A heating apparatus including, in com-

bination, a gas burner having a mixing tube formed with a web at its mouth, said web being apertured to provide an air inlet, a gas nozzle extending into the end of said mixing tube, and a shutter valve rotatable

• about the nozzle and on the end of said tube, the web of the tube and the shutter valve

having each a radial slot capable of registration to permit relatively lateral movement of the part.

In testimony whereof, I have affixed my signature hereto.

HENRY W. O'DOWD,
